UNITED STATES PATENT OFFICE.

CHARLES W. EISELE, OF FLINT, MICHIGAN.

LAMP DIMMER.

1,426,162.

Specification of Letters Patent. Patented Aug. 15, 1922.

Application filed October 18, 1920. Serial No. 417,776.

To all whom it may concern:

Be it known that I, CHARLES W. EISELE, a citizen of the United States, residing at Flint, in the county of Genesee and State of Michigan, have invented certain new and useful Improvements in Lamp Dimmers, of which the following is a specification.

This invention relates to lamps, and more particularly to means for regulating the intensity of illumination. The invention is particularly applicable to head lights for automobiles, motor boats, tractors or other vehicles, but may be adapted to lamps for other purposes, and comprises a further development and amplification of the invention disclosed in my Patent No. 1335727, dated April 6, 1920.

The invention contemplates a head light or other lamp having dimming means comprising a tubular shield or sleeve, surrounding the lamp bulb or other illuminating element, the illuminator and tubular shield being relatively movable in a longitudinal direction, whereby the rays of light from such lamps are intercepted or permitted to be reflected by the usual reflector.

The object of the present invention is to improve the control means for the reciprocating element and to provide automatic locking means therefor, for locking the movable element in its retracted position.

A further object of the invention is to provide electrical impulse operated control means whereby the reciprocating element whether the same be the tubular shield or the lamp therein is reciprocated and locked in its retracted position by one electrical impulse and is automatically released by a succeeding electrical impulse.

40 A further object of the invention is to associate and arrange the operating parts whereby they will be compactly arranged and may be easily and cheaply manufactured, having but few operating parts and unlikely to get out of repair.

With the above primary and other incidental objects in view as will more fully appear in the specification, the invention consists of the features of construction, the parts and combinations thereof, and the mode of operation or their equivalents as hereinafter described and set forth in the claims.

Referring to the drawings, Fig. 1 is a sectional view of the assembled lamp embodying the invention forming the subject matter hereof, showing the tubular shield

or interceptor as the reciprocatory member which is in its forward or operative position. Fig. 2 is a detail view of a modification showing the lamp and its support as the reciprocating element. Figs. 3 and 4 are detail perspective views of the interengaging locking members. Fig. 5 is a detail plan view of the locking members in engaged relation. Fig. 6 is a sectional view of a modification. Figs. 7 and 8 are detail views of the detent employed in the construction shown in Fig. 6.

Like parts are indicated by similar characters of reference throughout the several views.

Referring to the preferred form of embodiment shown in the drawings, 1 is the lamp housing having the usual transparent glass face 2. The transparent face 2 is carried in the frame 3, which forms a removable closure for the housing 1. Within the housing 1 is located a reflector 4 of the customary parabolic form, having positioned at its focal point an incandescent electric bulb or other illuminating element 5. In the construction shown in Fig. 1 the illuminating element 5 is stationarily mounted upon a supporting stem 6, projecting through an opening in the apex of the parabolic reflector 4. In Fig. 2 this construction is somewhat modified, by mounting the lamp bulb or illuminating element 5' upon a reciprocating support or stem 6', which likewise projects through a central opening at the apex of the reflector 4. Under its normal condition of use the rays of light emanating from the bulb or illuminating element 5 or 5' are reflected from the inner face of the parabolic reflector 4. The reflector 4 is so proportioned that the light rays will be condensed in the field of illumination and will be projected in substantially parallel rays, as is usual in lamps of this character.

Without the use of the reflector 4 the illuminating element 5 or 5' affords but a limited degree of illumination. Therefore, by intercepting the rays of light emanating from the lamp and permitting only a limited proportion of the light rays to reach the reflector 4, the brilliancy or intensity of illumination may be regulated. To dim the lamp by intercepting the rays of light, thereby reducing materially the intensity of the reflected light, there is provided a tubular interceptor shield or sleeve 8 which surrounds the illuminating element 5 when the

intensity of the light is to be reduced. In the construction shown in Fig. 1 this effect is achieved by reciprocating the sleeve or interceptor 8 forwardly in relation with the stationary light element 5, whereby the forward end of the interceptor sleeve will enclose the lamp and intercept all or the greater portion of the light rays, which would otherwise reach the reflector 4. It is desirable that a small portion of these light rays be allowed to reach the marginal rim of the reflector to afford a low degree of diffused illumination when the light is dimmed. However, if desired the interceptor 15 may be allowed to project to such extent as to cut off entirely all the light rays from the reflector 4. No light rays being permitted to reach the reflector the only illumination afforded will be that of direct light in a forwardly direction. In the operative position of the member, the interceptor or shield will not interfere with the illumination of the reflector 4, and the full light value or intensity of the reflected light may 25 be obtained. By adjusting the stop means hereafter mentioned, a greater or less area of the reflector may be utilized, thereby varying the degree or intensity of the illumination accordingly. In the construction 30 shown in Fig. 2 this result is achieved by reciprocating the lamp whereby it may be retracted within the stationary interceptor or projected therebeyond to the focal point of the parabolic reflector 4. To effect the 35 reciprocation of the interceptor or shield 8 of the construction shown in Fig. 1, or the lamp support 6 of Fig. 2, a solenoid 10 is employed.

As thus far described, the construction is 40 substantially that disclosed in my prior patent aforementioned, except that in the present instance the solenoid 10 is differently located in relation with the lamp support and shield.

In the present instance, the coil or winding 10 of the solenoid is concentrically positioned in relation with the lamp support 6 and shield or interceptor 8. As shown in Fig. 1 this solenoid is mounted upon a supporting plate or base 11, fixedly secured to the interior of the housing 1, and axially concentric therewith. Projecting inwardly from the base plate or support 11 and secured thereto concentrically in spaced relation with the coil or winding 10 is a guide tube 12, within which is mounted the supporting stem 6 of the lamp element 5. This lamp support 6 is stationary within the tube 12 while surrounding the tube 12 and slidably mounted thereon is the shield or interceptor 8. This interceptor in its forward position projects beyond the end of the tube 12 and encloses the lamp element 5. Interposed between the interceptor 8 and the base or supporting plate 11 is an ejector

spring 13 to actuate the interceptor or shield 8 forwardly. The shield or interceptor 8 is limited in its forward movement by stop nuts 14 carried upon a rod 15 projecting from the supporting plate 11. This rod 15 70 not only carries the stop nuts 14 which limit the throw of the interceptor or shield, but it also affords an auxiliary guide for the shield and prevents its rotation about the guide tube 12. 75

The interceptor 8 is preferably formed of sheet steel or iron, and comprises the reciprocatory core of the solenoid 10. That is to say, the solenoid core is of hollow or tubular form enclosing the lamp 5 when projected 80 forwardly under the influence of the spring 13 and exposing the lamp when retracted by the magnetic influence of the solenoid coil 10. The winding 10 of the solenoid is of such capacity and the tension of the ejector 85 spring 13 relatively proportioned thereto, that an electrical impulse through the coil or winding 10 will cause the electromagnetic coil to attract its core 8, forming the interceptor, against the tension of the spring 13, 90 drawing it rearwardly quickly and forcibly. The electro-magnetic forces of the coil naturally tend to balance the retracted tubular core 8 comprising the interceptor at a medial position within the coil or winding. 95 However, this is resisted by the ejector spring 13 which constantly tends to displace the interceptor or core forwardly. The force or violence with which the tubular core or interceptor 8 is retracted by the electrical 100 influence affords it such momentum that it will slightly overthrow or travel beyond its normal retracted position.

To automatically lock the reciprocatory element in its retracted position, there is attached to the rear of the interceptor 8 a rearwardly projecting finger 16, having therein a hole or eye 17, and comprising a catch or keeper for the engagement of a detent 18. The detent finger 18 is pivoted on a trunnion pin 19, mounted in a suitable bracket or supporting ears 19 on the base plate 11, and projects forwardly therefrom. The detent finger 18 is provided with an upturned extremity 20 for engagement in the eye or opening 17 of the catch finger 16. This detent finger 18 is carried by an oscillatory U-shaped armature yoke 21, extending about the guide tube 12, and carrying at its extremity, pads or small bodies of iron to be 115 attracted by the magnetic influence of the core 8. The pivotal connection of the interconnected armature yoke, and detent finger is such that when the detent 18 and finger 16 are interengaged, the pull is in a straight line, 120 and the armature yoke and detent finger are normally held elevated in retracted or engaging position. To insure the maintenance of this position, particularly when an automobile is descending a hill, a light spring 23 is 125 130

- provided which tends to draw the interconnected armature yoke and detent finger 18 rearwardly with the finger extending into the path of the catch finger 16. The armature yoke 21 also extends into the path of travel of this catch finger 16 and upon the retractive movement of the interceptor 8, the inclined end of the finger 16 engages and depresses the detent 18 and continuing its movement the yoke 21 is engaged by the finger 16 with sufficient impact to force the yoke 21 rearwardly against the influence of gravity assisted by the light spring 23, thereby turning the detent finger 18 upwardly 15 with its upturned extremity projected within the eye or opening 17 of the catch finger 16. The rebound of the interceptor 8 under the influence of the spring 13 upon the interruption of the electric current will cause the rearward end of the eye or opening 17 to engage the upturned end of the detent finger 18 to hold the sleeve or interceptor in its retracted position. While the pads or bodies 22 of metal carried by the armature yoke 21 are within the range of magnetic influence 20 of the core 8, the momentum with which the interceptor or sleeve 8 is attracted is sufficient to overcome the attraction of the armature yoke, upon the impact of the catch finger 16 therewith. The detent finger being thus oscillated upwardly into engagement with the catch finger 16, holds the retracted core or interceptor by the tension of the spring 13. It will be understood that this movement of the core is effected by merely a 25 momentary impulse through the winding 10. The opening or eye 17 of the finger 16 is of such length as to afford some clearance in relation with the upturned end of the detent finger 18 permitting a slight retrograde movement of the interceptor or core 8 under the influence of the spring 13, into locking engagement.
- When it is desired to release the interceptor for the purpose of dimming the lights, another impulse is transmitted through the solenoid winding 10. The core or interceptor 8 at this time being held in a substantially neutral or balanced position, and the spring 13 being under tension the core will not respond to the magnetic influence, but such magnetic influence will be exerted through the core 8 upon the pads or bodies 22, carried by the armature yoke to attract the armature yoke and thereby oscillate the detent finger 18 downwardly out of engagement with the catch finger 16. This releases the interceptor or core 8, which is then projected forwardly under the influence of the spring 13 to its operative position. Thus it will be seen but a momentary impulse is required to retract and lock the core or interceptor, the engagement of which is effected automatically and a second impulse 60 only is required to release the core or inter-
- ceptor from its locked engagement. The increasing tension of the spring 13 during the retractive movement of the core or interceptor affords a cushion to take up the impact of the core, under the influence of magnetic attraction.
- The construction shown in Fig. 2 operates substantially identical with that heretofore described, except that the interceptor or shield 8' is stationary while the lamp support 6' is slidably mounted within the coil 10 and comprises the core thereof. The locking and release of the reciprocating lamp supporting core may be effected in the manner before described by detent mechanism 75 as shown in either Figs 1 or 6. The construction of Fig. 2 comprises merely a reversal of the relatively movable members illustrated in Fig. 1.
- In Fig. 6 there is shown a further modification in which a latch member 25 having a beveled nose 26 projects through the wall of the guide tube 12 and is engaged and depressed by the interceptor sleeve 8 in its rearward movement. The detent 25 is carried by an armature 27 extending within the range of magnetic influence of the coil 10'. In the drawing the interceptor sleeve comprising the solenoid core is shown retracted and the detent arm elevated into 90 locking engagement therewith. The detent arm 25 is preferably of brass and is carried by the armature body 27 of iron or steel. The armature is pivoted in a U-shaped bracket 28 secured about the tube 12. 100 The armature is so pivoted as to form a counter balance weight actuating the detent 25 into engaging position by gravity. To insure operation on steep grades where gravity control may be disturbed, an auxiliary spring 29 is provided. The electric impulse through the core by which the interceptor 8 is retracted also effects the attraction of the armature 27 and so tips the detent arm downward to receive the interceptor. The impact of the retracted interceptor upon the armature 27 returns it to normal notwithstanding the attraction of the coil and so turns the nose 26 upward to 105 engaging position. At the end of the electrical impulse the detent arm is held in its elevated or engaging position by the gravity action of the armature assisted by the spring 29. Upon the transmission of a releasing impulse the armature 27 is again attracted, thereby depressing the detent nose 26 and permitting the interceptor to be projected forwardly under the influence of the spring 13. In this instance the spring 13 is of greater diameter than shown in the preceding figures, and is located adjacent to the outer periphery of the shield or interceptor and immediately within the coil 10.
- From the above description it will be apparent that there is thus provided a device 130

of the character described possessing the particular features of advantage before enumerated as desirable, but which obviously is susceptible of modification in its form, 5 proportions, detail construction and arrangement of parts without departing from the principle involved or sacrificing any of its advantages.

While in order to comply with the statute 10 the invention has been described in language more or less specific as to structural features, it is to be understood that the invention is not limited to the specific details shown, but that the means and construction herein disclosed comprise but one of several modes of putting the invention into effect, and the invention is therefore claimed in any of its forms or modifications within the legitimate and valid scope of the appended claims.

Having thus described my invention, I claim:

1. A lamp construction wherein, an illuminating element and a shield are relatively movable in relation with each other including, a spring tending to relatively move one of said members in one direction, and electromagnet adapted to relatively move said spring actuated member in the opposite direction, characterized by a pivoted 20 detent member, having an operating arm extending into the path of travel of the movable member, and operatively engaged thereby to positively actuate the detent to insure locking engagement thereof, said operating arm being subject to magnetic influence upon a subsequent impulse through said electromagnet to effect a reverse oscillation of the detent and release of the locked element.

2. A lamp construction wherein an illuminating element and a shield therefor are relatively movable in relation with each other, including a spring tending to relatively move one of said members in one direction, and means to retract the movable member against the tension of said spring with sufficient momentum to effect a degree of overthrow, beyond its normal retracted position, characterized by a mechanically 40 operated detent, actuated by the overthrow movement of the retracted member to lock said member against the tension of the spring and means to disengage said detent.

3. A construction wherein an illuminating element and a shield therefor are relatively movable in relation with each other, including a spring tending to relatively move one of said members in one direction, and means to retract the movable member against the tension of said spring characterized by a latch for engaging the retracted member and holding same against the tension of the spring and electrically controlled means to the influence of which 60 said latch is subject only when said movable

member is in its retracted position for disengaging said latch.

4. In a lamp, an illuminating element, a support therefor, and a shield for the illuminating member, said support and shield being relatively movable, a solenoid of which the movable member forms the core, a spring against the tension of which the solenoid core is attracted to relatively adjust said shield and illuminating element and means 70 for intermittently energizing said solenoid.

5. In a lamp, an illuminating element, a support therefor, and a shield for the illuminating member, said support and shield being relatively movable, a solenoid of which 80 the movable member forms the core, a spring against the tension of which the solenoid core is attracted to relatively adjust said shield and illuminating element, an automatically operated latch for locking the 85 movable member in its retracted position, and means for releasing the latch by the influence of said solenoid.

6. In a lamp, an illuminator support, a tubular shield, and an electromagnetic coil 90 concentrically arranged in relation with the illuminator support and tubular shield, one of the last mentioned members being movable under the influence of the electromagnetic coil, a spring against the tension of 95 which said member is movable, an illuminant carried by the support, and means to energize said coil.

7. In a lamp, a solenoid having a tubular core, an illuminant enclosed within the tubular core in one position of adjustment thereof, and an electric circuit controlling the solenoid to effect the movement of the tubular core in relation with said illuminant.

8. In a lamp, an illuminator and a tubular shield therefor one of which is relatively movable in relation with the other, the shield enclosing the illuminator in one position of adjustment, and an electromagnetic coil concentrically arranged in relation with said shield and illuminator controlling the relative adjustment of said members.

9. In a lamp, an illuminator and a shield therefor one of which is movable in relation with the other, an electromagnet controlling 115 the relative movement of said member, a pivoted detent extending into the path of the relatively movable member and oscillated into operative engagement with the movable member by its engagement thereby at the 120 limit of the travel of said movable member under the influence of the electromagnet, an extension of said detent projecting into the field of influence of the electromagnet and attracted thereby to release the movable 125 member.

10. In a lamp, an illuminator and a shield therefor one of which is movable in relation with the other, electrically operated means for controlling the relative adjust- 130

ment of said members, and a detent for the movable member adapted upon one electric impulse to lock said member in adjusted position and upon a succeeding impulse to release said movable member.

11. In a lamp, an illuminator and a shield therefor relatively movable in relation with each other, means for actuating the movable member, said movable member being projected beyond a normal retracted position by the momentum of its retractive movement, a detent for the movable member moved into operative engagement therewith by the overthrow movement thereof, and means for releasing said detent.

12. A lamp construction wherein an illuminating element and a shield therefor are relatively movable in relation one with the other, characterized by a latch for the movable member, means for retracting the movable member with sufficient momentum to effect a degree of overthrow beyond its normal locked position, said latch being actuated by such overthrow movement to positively move the same into engaging position, and means to effect the release of the latch.

13. A lamp construction wherein, an illuminating element and a shield therefor are relatively movable in relation one with the other by electromagnetic means, characterized by a latch for the movable member out of the field of magnetic influence when the

movable member is in one position of adjustment, but brought into the magnetic field by the relative movement of such movable member whereby the succeeding electrical impulse through said electromagnetic means will influence said latch to effect an operative movement thereof.

14. A lamp construction wherein an illuminating element and a shield therefor are relatively movable in relation one with the other under the influence of a solenoid of which the movable member comprises the core, characterized by a magnetically influenced latch, attracted by the magnetism of such solenoid core element when the latter is in one position of adjustment but uninfluenced upon the shifting movement of such core element.

15. In a lamp, a solenoid, a hollow core therefor, a fixed lamp enclosed in the hollow core when said core is at one limit of its stroke and exposed when the core is at the opposite limit of its stroke, and detent means for the core releasable under magnetic influence of the core.

In testimony whereof, I have hereunto set my hand this 21st day of September, A. D. 1920.
